UNITED STATES PATENT OFFICE.

LOUIS MEYER, OF MILFORD, ILLINOIS.

DOOR-OPERATING MECHANISM.

1,265,229.

Specification of Letters Patent. Patented May 7, 1918.

Application filed June 27, 1917. Serial No. 177,308.

To all whom it may concern:

Be it known that I, LOUIS MEYER, a citizen of the United States, residing at Milford, in the county of Iroquois and State 5 of Illinois, have invented a new and useful Door-Operating Mechanism, of which the following is a specification.

It is the object of this invention to provide novel means for swinging a door to and from an open position from a distant point, and to provide novel means for holding the door in an open or a closed position.

With the above and other objects in view which will appear as the description proceeds, the invention resides in the combination and arrangement of parts and in the details of construction hereinafter described and claimed, it being understood that changes 20 herein disclosed can be made within the scope of what is claimed, without departing from the spirit of the invention.

In the accompanying drawings:—

Figure 1 shows in front elevation, a door-operating mechanism embodying the present invention;

Fig. 2 is a top plan of the structure shown in Fig. 1, parts being omitted;

Fig. 3 is a vertical section of the structure shown in Fig. 1, one of the doors being swung into a position at right angles to the wall of the building;

Fig. 4 is a fragmental elevation showing a part of the door-operating mechanism.

The numeral 1 indicates a support, such as the wall of a building. The support 1 has a doorway 2. The doorway 2 is controlled by a first door 3 hinged at 4 to the wall 1, and by a second door 5 hinged at 6

40 to the wall 1.

Mounted on the wall 1 above the doorway 2 is a horizontal U-shaped strip 7. A vertically slanting strip or brace 8 is secured at its inner, upper end to the support 1. The 45 outer, lower end of the strip 8 terminates in a vertical arm 9 attached by a securing element 10 to the bend of the horizontal U-shaped strip 7. The strip 8 includes a horizontal part 11, the arm 9 having a horizontal 50 tal finger 12.

Journalized in the members 11 and 12 is a vertical shaft 14 provided at its lower end with a fork 15. A nut 75 or the like on the upper end of the shaft 14, prevents the 55 shaft 14 from sliding downwardly.

The numeral 16 denotes a vertically swinging main link. The outer end of the main link 16 is pivoted at 17 in the fork 15 of the shaft 14. A rule joint 18 connects the inner end of the main link 16 with the outer end of an auxiliary link 19. The inner end of the auxiliary link 19 has a fork 20. The pivot element 21 is mounted in the fork 20. The pivot element 21 passes through a head 22 disposed in the fork 20, the head being mounted on the upper end of a vertical shaft 23 journaled in bearings 24 and 25 on the outer face of the second door 5. The shaft 23 has a collar 26, which, coacting with the bearing 24, holds the shaft 23 in the 60 bearings 24 and 25 against downward movement. A helical spring 27 is coiled around one end of the pivot element 21. One end of the helical spring 27 is fashioned into an arm 28 engaged as indicated at 29 across the upper edge of the auxiliary link 19. The other end of the helical spring 27 is extended to form an arm 30 engaged as shown at 31 across the rear edge of the shaft 23, 65 below the bearing 24.

A hanger 32 is mounted on the wall 1. The inner end of a bar 33 is pivoted at 34 to the hanger 32, for horizontal swinging movement. The rear edge of the bar 33 is provided with concaved seats 35 and 36, defining an apex 37 therebetween. The outer end of the bar 33 is connected by means of a retractile spring 38 with the wall 1. Near to its hinged edge, the second door 5 has a standard 39 which projects above the upper 70 edge of the door. Mounted to rotate on the upper end of the standard 39 is a grooved wheel 40 engaging the rear or inner edge of the bar 33.

A flexible element 41 is connected as 75 shown at 76 with the main link 16. The flexible element 41 is rove across a sheave 42 fixed to and depending from the strip 8. From the sheave 42, the flexible element 41 is extended across a pulley 43 carried by the 80 support 1 adjacent the hinged edge of the door 3. From the pulley 43, the flexible element 41 is extended downwardly through a guide 44 on the wall 1, the flexible element 41 being thence extended, as shown at 45, Fig. 100 105 3, rearwardly, across a pulley 46 carried by a post 47. The post 47 may be located at any desired distance from the building of which the wall 1 constitutes a part. A branch line 48 is connected with the flexible 110

element 41 below the pulley 43. The branch line 48 is extended through the guide 44 and thence is prolonged forwardly, as shown at 49, in front of the wall 1, around a pulley 50 carried by a post 51 which is located at any desired distance in front of the building of which the wall 1 constitutes a part.

As a preliminary statement, it may be set forth that the flexible element 41 may be manipulated, either from in front of the building, by pulling on the end 49 of the flexible element, or it may be actuated at a point remote from the building, by pulling on the end 45 of the flexible element.

- 15 When the door 5 is closed, the links 16 and 19 are in axial alinement and are horizontally disposed, and since these links are connected by the rule joint 18, the door 5 will be held in a closed position. When the flexible element 41 is drawn upon, the same rides over the sheave 42 and causes the links 16 and 19 to knuckle upwardly into the position of Fig. 3. During this operation, the spring 27 is put under tension, because its arms 28 and 30 are engaged, respectively, with the link 19 and with the shaft 23. When the door 5 is swung toward an open position, the wheel 40 rides out of the seat 35, and by the time that the door 5 stands 30 at right angles to the wall, the wheel is on the apex 37. This operation swings the bar 33 away from the wall 1, and the spring 38 is put under tension. The inertia of the door 5 moves the door toward an open position, beyond a position at right angles to the wall 1. The wheel 40 then rides into the seat 36, and the spring 38 reacting on the bar 33, swings the door 5 into a completely open position, it being recalled that the 40 wheel 40 is mounted on the standard 39 which is connected with the door 5. The links 16 and 19 now knuckle downwardly into axial alinement, thus holding the door 5 in a fully open position. The spring 27 and its arms 28 and 30 aid in swinging the links 16 and 19 into alinement as aforesaid. It will be understood that while the door 5 is swinging from a closed position to an open position, the shaft 14 rotates in 50 the parts 11 and 12 of the strip 8, the shaft 23 rotating in the bearings 24 and 25 on the door 5.

When it is desired to close the door 5, the process above described is reversed, the flexible element 41 knuckling up the links 16 and 19 into the position of Fig. 3, and the door 5 finally swinging into a closed position, whereupon the links 16 and 19 will knuckle downwardly into alinement, the door 5 being held in a closed position, since the links 16 and 19 are connected by the rule joint union 18.

In order that the door 2 may be controlled by the movement of the door 5, a rod 80 may be pivoted at 81 to the rear face of the door

5, the rod 80 being pivoted as shown at 82 to an offset bracket 83 on the door 2. When the door 5 stands in a fully open position, that is, when the door 5 is swung around until it is approximately parallel with the wall 1, the door 3 stands approximately at right angles to the wall 1. It will be obvious to those skilled in the art that the device forming the subject matter of this application will work either in connection with one door or in connection with two doors.

What is claimed is:—

1. In a device of the class described, a support; a door hinged to the support; a frame outstanding from the support; a shaft journaled in the support; a shaft journaled on the door and disposed parallel to the shaft in the frame; links having their outer ends hinged to the respective shafts for swinging movement in a plane defined by the axes of the shafts; a rule joint connecting the inner ends of the links; means for manipulating the links from a distant point; a bar hinged at one end to the support; yieldable means for moving the other end of the bar inwardly with respect to the support, said yieldable means being effective to aid in swinging the inner ends of the links downwardly and to aid in closing the rule joint when the door is closed and when the door is fully opened; and a projection on the door, the projection being slidably engaged with the inner edge of the bar.

2. In a device of the class described, a support; a door hinged thereto; a frame outstanding from the support; a shaft journaled in the frame; a shaft journaled on the door and disposed parallel to the shaft in the frame; links hinged at their outer ends to the respective shafts for swinging movement in a plane defined by the axes of the shafts; a rule joint connection uniting the inner ends of the links; a bar hinged to the support; yieldable means for controlling the outward swinging movement of the bar, said yieldable means being effective to aid in swinging the inner ends of the links downwardly and to aid in closing the rule joint when the door is closed and when the door is opened; and a projection on the door, the bar being provided on its inner edge with seats and with an apex between the seats, the projection lying in one seat when the door is completely closed, and lying in the other seat when the door is fully opened, the projection being disposed on the apex when the door is at a point between a closed position and a fully opened position.

3. In a device of the class described, a support; a door hinged thereto; a horizontal frame outstanding from the support and located above the door; a brace extended downwardly from the support to the outer end of the frame; a shaft journaled in the outer end of the frame; a shaft journaled on

the door and disposed parallel to the shaft on the frame; an outer link having its forward end pivoted to the shaft on the frame; an inner link; a rule joint connecting the forward end of the inner link with the rear end of the outer link; a pivot element connecting the rear end of the inner link with the shaft on the door; means for operating the door from a remote point and including a flexible element attached to one link; and

a direction-changing idler on the brace, across which the flexible element passes.

In testimony that I claim the foregoing as my own, I have hereto affixed my signature in the presence of two witnesses.

LOUIS MEYER.
